UNITED STATES PATENT OFFICE.

HAROLD BINNEY, OF NEW YORK, N. Y.

CHANGE-MAKING MACHINE.

No. 844,654.

Specification of Letters Patent.

Patented Feb. 19, 1907.

Application filed September 15, 1903. Serial No. 173,224.

To all whom it may concern:

Be it known that I, HAROLD BINNEY, a citizen of the United States, and a resident of the borough of Manhattan, city, county, 5 and State of New York, have invented certain new and useful Improvements in Change-Making Machines, of which the following is a specification accompanied by drawings.

This invention relates to change-making machines, and its objects are to improve and simplify the construction of such machines, increase the accuracy and certainty of operation, and enable the different amounts of change to be automatically produced in the 15 machine with a fewer number of operations than heretofore.

Further objects of the invention will hereinafter appear; and to these ends the invention consists of a machine for carrying out 20 the above objects embodying the features of construction, combinations of elements, and arrangement of parts having the general mode of operation substantially as herein-after fully described and claimed in this 25 specification and shown in the accompanying drawings, in which—

Figure 1 is a rear end elevation of the machine. Fig. 2 is a side elevation with one of the sides of the inclosing casing removed, 30 showing the interior construction of the apparatus. Fig. 3 is a top plan view of the machine with a portion of the top of the casing broken away. Fig. 4 is a front end elevation of the machine with the front of the 35 casing removed to show the interior construction. Fig. 5 is an enlarged detail side view of one of the pusher-rods for manipulating one of the coins. Fig. 6 is an enlarged detail side view of another one of the pusher- 40 rods for manipulating the coins. Fig. 7 is a much enlarged detail end view, partly in section, of a coin and one of the pusher-rods. Fig. 8 is an outside face view of the pusher-rod-controlling disk adapted to be rotated 45 into predetermined positions. Fig. 9 is a rear elevation showing in detail the connections for the pusher-rods. Fig. 9 is taken on a line just in the rear of the pusher-rods and between the disk and the pusher-rods. 50 Fig. 10 is an enlarged detail side view, partly broken away, of the automatic mechanism for recording the amount of change made at each operation.

Referring to the drawings, A represents 55 a suitable box or casing containing the operative connections of the apparatus and pro-

vided with three trays or troughs B, C, and D, in which the change is deposited when made. Means are provided for causing the change to be deposited in any one of the 60 troughs B, C, or D. Upon the top of the casing are shown holders for the coins in the form of cylinders. The holder 50^a contains a column of fifty-cent pieces, the holder 25^a contains twenty-five-cent pieces; the two 65 holders 10^a contain ten-cent pieces, the holder 5^a contains five-cent pieces, and the two holders 2^a contain one-cent pieces, as does also the holder 1^a.

The columns of coins in the holders are 70 supported upon the cross-slats E and the pusher-rods F. The pusher-rods F are provided with notches G in their ends, in which the lowermost coin of the column in a holder rests, as shown in Fig. 5. The notches G in 75 the pusher-rods F are just of sufficient depth to hold the thickness of the coin. When the pusher-rod is moved forward, the lowermost coin of a column is carried therewith, and when the coin moves beyond the cross-slat 80 E it will be seen that there will be no support for the sides of the coin and it will fall sidewise from the pusher-rod F. As shown, the upper edge of the pusher-rod is beveled at H to cause the coin to fall quickly therefrom. The pusher-rods I are provided with notches or recesses J of sufficient depth to accommodate the thickness of two pennies, so that two cents in change can be made. The 85 notches G in the pusher-rods F are made of 90 sufficient depth, as stated, to accommodate the coins in the holders, beneath which said rods operate.

Beneath the holders within the casing is arranged a hopper K, discharging into the 95 chutes L, O, and P. The chutes L and P are supported within the casing and arranged to discharge into the troughs D and B, respectively, while the chute O is supported upon a rod Q, pivoted at R upon the casing, 100 and means are provided for shifting the chute O transversely of the machine. In the position of the chute O shown in Fig. 4 the coins will be discharged from the mouth S of the hopper K into the chute P and from 105 thence to the trough B. When the chute O is in a central position beneath the mouth S of the hopper K, the coins will be discharged through the chute O into the front trough C. When the chute O is 110 moved to the limit of its position to the right looking at Fig. 4, a lip T, connected

to the chute O, is brought into position beneath the hopper K, and the coins are deflected by the lip T into the chute L and from thence they are deflected in the trough D.

Suitable means are provided for manipulating the chute O, as shown, an arm U being connected to the longitudinally-extending rod V, pivoted on the bracket W, 10 while a rod X connects the arm U and rod Q. The longitudinally-extending rod V is provided with a milled knob Y outside of the casing and at the front thereof, so that the point of delivery of the coins from the hopper K may be controlled as desired.

The manner in which coins of different denominations may be delivered to the receptacles or troughs B, C, and D has been described, and means will now be described 20 for setting the machine to deliver any desired amount of money in change up to one dollar. The machine, as herein to be described, is constructed, as stated, to deliver change up to one dollar; but the principles 25 upon which the machine is built may be extended to include larger machines for delivering change in any desired amounts without departing from the spirit of this invention. In other words, without changing the principles 30 of the machine it may be made larger or smaller, as desired, the description herein contained being applicable to a machine which is designed to illustrate the invention fully.

35 It is obvious that according to the number of pusher-rods F and I actuated at the same time change in different amounts will be delivered into the hopper K, and at the front of the machine a disk a is provided constructed to control the operation of the 40 pusher-rods F and I. Means are also provided in connection with the disk a for registering the amount of change delivered at each operation.

45 The disk a is carried upon a shaft b, slidably mounted in the bearing or hub c, connected to the casing of the machine, while upon the outside of the casing is an indicating-disk d, provided with numbers on its periphery from "0" to "99," adapted to coöperate with corresponding numbers arranged around the same on the casing. The disk d is provided with a hub e, and the construction of this portion of the apparatus 50 is such that the shaft b, carrying the disk a, may be pushed forward or moved longitudinally relatively to the casing and the hubs c and e, while at the same time the disks a and d may be rotated by rotating 55 the handle f, connected to the shaft b. A suitable spring g is shown adapted to be compressed between the hub e and the handle f, thereby tending to return the disk a and handle f to the position shown in full 60 lines in Fig. 3 after the handle f has been

pushed forward to the position shown in dotted lines in said figure. Any suitable means may be provided for causing the disk d to rotate with the shaft b, but affording provision for the longitudinal movement 70 of the shaft b relatively to the disk d—as, for instance, the shaft may be provided with a feather and the disk-hub with a slot through which the feather slides.

In this instance the pusher-rods F and I 75 are slidably mounted intermediate their length in a frame h, while their outer ends move in the grooves i in the slats E. The inner or rear ends of the pusher-rods, as shown, are pivoted to the upper end of vertically-extending rods j, separately pivoted upon a shaft k at the lower portion of the machine, said shaft being carried in the brackets l o. Centrally of the vertically-extending rods j are outwardly-extending arms or fingers p, 80 which, as shown, project toward the revolute and longitudinally-movable disk a, so that as said disk a is moved forward longitudinally of the machine certain projections or fingers thereon, according to the rotative position of the disk, will abut against the fingers p on the rods j and rock said rods about their pivots on the shaft k, thereby forcing certain of the pusher-rods forward and pushing certain of the coins from beneath the coin-holders, thereby permitting said coins to drop into the hopper K.

The projections on the front face of the disk a correspond with the face view of said disk, as shown in Fig. 8. Fig. 8 is taken looking at the rear of the disk, and consequently the projections are shown in dotted lines on the opposite face. It is to be assumed that the disk a is divided in accordance with the numbers on the periphery of the indicating-disk d, because said indicating-disk d determines the amount of change and the rotative position of the operating-disk a. In laying out the operating-disk a a radial line was drawn from the center of the disk to the point on the periphery marked "0" in Fig. 8, and upon this radius was marked off eight numerals, corresponding to the amount of change afforded by the different coin-holders. These numbers appear as follows: "1, 2, 2, 5, 10, 10, 25, 50." In illustrating this machine it is found convenient to make change according to the above numbers—that is to say, one cent may be made, or fifty cents, or twenty-five cents, or combinations of the same, or combinations of these amounts with ten cents, five cents, or two cents. For convenience in making ten-cents amounts ten cents is represented twice and two cents is represented twice. From each of the ninety-nine divisions around the periphery of the disk a radii are drawn, and concentric circles are drawn through the points indicated by the numbers "1, 2, 2, 5," &c. It will readily be seen, then, that at the intersecting 115 120 125 130 lines in Fig. 3 after the handle f has been

points at the radii and concentric circles positions may be marked for different amounts from one cent up to one dollar along the radii. The first radius from the initial position represents one cent; the second radius, two cents; the third radius, three cents—that is to say, one cent and two cents—and so on. At the points so laid out at the intersections of the radii and concentric circles projections 5 of *q* are provided upon the outer operating-face of the disk *a*, while between the projections *q* spaces are left. No projections are formed on the initial line provided with the numerals "1, 2, 2, 5," &c., so that with the disk *a* in 10 the position shown in Fig. 8, corresponding to the position of the indicating-disk *d*, (shown in Fig. 1,) the handle *f* might be pushed forward as many times as desired and none of the pusher-rods would be operated, because 15 the fingers *p*, connected to said rods, would not be hit by any projection on the face of the operating-disk *a*. Let it be desired to deliver one cent into one of the troughs *B*, &c., then the indicating-disk *d* is turned 20 counter-clockwise in the direction of the arrow of Fig. 8 until the number "1" on the periphery of the indicating-disk *d* registers with the zero-mark on the casing. The projections *q* at the intersection of the radii 1 and 25 the concentric circle 1 of Fig. 8 will then lie in a position to abut against the finger *p*, connected to the pusher-rod *F*, which controls the one-cent pieces in the holder *1^a*, and therefore when the handle *f* is pushed forward, carrying the disk *a* forward, the pusher-rod *F* for controlling one-cent pieces will be manipulated, and a one-cent piece will be delivered into one of the troughs. 30

In laying out the operating-disk *a* in order 35 to reduce the number of independent and separate projections *q* upon the face thereof these projections were combined into ribs or strips *r* of varying lengths, according to the number of projections which lie side by side 40 substantially touching each other.

This invention is not to be understood as being limited to the construction of fingers *p* and projections *q* on the disk, as described, for it is obvious that many different mechanical constructions might be provided for operating the pushers *F* and *I* from a rotatable disk *a*, and any suitable means may be provided for carrying out this object without departing from the spirit of this invention. 45

The extreme outer periphery of the inner or front face of the disk *a* is provided with projections *t*, having type at their outer ends corresponding to the numbers shown around the disk *a* on Fig. 8, and means are provided 50 for taking imprints from these type each time that the disk *a* is operated. In Figs. 2 and 10, 60 represents a roller carried by the shaft 61, pivoted in the brackets 62 and *o*. Connected to the shaft and roller is a ratchet- 55 wheel 63, provided with a stop-pawl 64. The

bracket *o* is provided with an upwardly-extending arm 65, upon which is pivoted a rod 66, carrying at its lower end an actuating-pawl 67, adapted to coöperate with the ratchet-wheel 63 and connected to operate 60 the roller 60 each time that the disk *a* moves rearward after having been pushed forward. In other words, the connections are such that the ratchet-wheel 63 is rotated one step each time that the disk *a* moves backward. As 65 shown, the upper end of a rod 66 is confined between collars 68 on the reduced end 69 of the shaft *b*. The inner portion of the reduced end 69 of the shaft *b* is rotatably and slidably supported in the standard 70. According to the construction described it will be seen that as the shaft *b* is pushed forward the actuating-pawl 67 will be dragged over the teeth of the ratchet-wheel 63 without 75 engaging the same, and then as the shaft *b* is moved backward the rod 66 will be again rocked upon its pivot 71 and the ratchet-wheel 63 will be rotated one step to feed the paper ribbon 72 in readiness for the next impression from one of the type on the outer 80 periphery of the disk *a*. Each time that the disk *a* is pushed forward to make the desired amount of change an impression is taken upon the ribbon 72 from one of the type, indicating the amount of change made. 85

In setting the indicating-disk *d* to indicate the amount of change desired it is simply necessary to bring any one number on the disk *d* beneath the appropriate number on the casing, so that the difference between 90 said numbers will equal the amount of change desired, and each time that the indicating-disk is turned it should be turned in the direction of the arrow shown in Fig. 8, or counter-clockwise. The indicating-disk *d* may 95 be manipulated in various ways, and various combinations of figures may be used to produce the desired results or else the zero-point may always be used, and the number indicating the amount of change desired is then 100 simply brought opposite the zero-mark on the casing and then the handle *f* pushed inward or forward.

Obviously some features of this invention may be used without others, and the invention may be embodied in widely-varying forms. 105

Therefore, without limiting the invention to the construction shown and described nor enumerating equivalents, I claim and desire to obtain by Letters Patent the following 110 ing—

1. A change-making machine comprising a plurality of coin-discharging means controlling coins of different denominations, a part 115 movable in two directions and adapted to coact with said discharging means to deliver coins having a predetermined total value from that of the smallest coin to that of any multiple thereof within the capacity of the 120

machine, means for moving said part primarily to determine the number of coins of each denomination to be discharged and secondarily to operate said discharging means, and 5 printing means coöperating with said moving part for recording the value of the coins discharged.

2. A change-making machine comprising a plurality of coin-discharging means controlling 10 coins of different denominations, a disk adapted to coact with said discharging means to deliver coins having a predetermined total value from that of the smallest coin to that of any multiple thereof within 15 the capacity of the machine, means for successively rotating said disk to a desired point and moving it to operate said discharging means, and printing means coöperating with 20 said moving part and actuated thereby for recording the value of the coins discharged.

3. A change-making machine comprising a plurality of coin-discharging means controlling coins of different denominations, a disk adapted to coact with said discharging means 25 to deliver coins having a predetermined total value from that of the smallest coin to that of any multiple thereof within the capacity of the machine, integral means for successively rotating said disk and moving it longitudinally 30 of its axis to operate said coin-discharging means, and printing means coöperating with said moving part for recording the value of the coins discharged.

4. In a change-making machine, a casing, 35 a plurality of coin-holders for coins of different denominations, means for discharging coin from said holders, a disk adapted to coact with said discharging means to deliver coins having a predetermined total value 40 from that of the smallest coin to that of any multiple thereof within the capacity of the machine, means extending out of said casing for successively rotating said disk to a desired point and for moving it to operate said 45 discharging means, and means on said casing for indicating the rotation of said disk, and printing means coöperating with said moving part and actuated thereby for recording the value of the coins discharged.

5. In a change-making machine, a plurality of coin-discharging means controlling coins of different denominations, a part movable in two directions and adapted to coact 55 with said discharging means to deliver coins having a predetermined total value from that of the smallest coin to that of any multiple thereof within the capacity of the machine, means for moving said part primarily to determine the number of coins of each 60 denomination to be discharged and secondarily to operate said discharging means, means for supporting in the path of said moving part a record strip or sheet, and means on said moving part for imprinting on

such strip numerals corresponding to the 65 value of the coins discharged.

6. In a change-making machine, a plurality of coin-discharging means controlling coins of different denominations, a part movable in two directions and adapted to coact 70 with said discharging means to deliver coins having a predetermined total value from that of the smallest coin to that of any multiple thereof within the capacity of the machine, means for moving said part primarily 75 to determine the number of coins of each denomination to be discharged and secondarily to operate said discharging means, means for supporting in the path of said moving part a record strip or sheet, means on said 80 moving part for imprinting on such strip numerals corresponding to the value of the coins discharged, and means actuated through said moving part for advancing such strip step by step.

7. A change-making machine consisting of a plurality of coin-discharging means controlling coins of different denominations, a disk adapted to coact with said discharging means to deliver coins having a predetermined total value from that of the smallest coin to that of any multiple thereof within the capacity of the machine, means for successively rotating said disk to a desired point and moving it to operate said discharging 90 means, means for supporting in the path of the longitudinal movement of said disk a record strip or sheet, and type on said disk for imprinting on such strip numerals corresponding to the value of the coins discharged.

8. A change-making machine consisting of a plurality of coin-discharging means controlling coins of different denominations, a disk adapted to coact with said discharging means to deliver coins having a predetermined total value from that of the smallest coin to that of any multiple thereof within the capacity of the machine, means for successively rotating said disk to a desired point and moving it to operate said discharging 95 means, means for supporting in the path of the longitudinal movement of said disk a record strip or sheet, type on said disk for imprinting on such strip numerals corresponding to the value of the coins discharged, and means actuated by the rotary movement of said disk for advancing such strip 100 step by step.

9. In a change-making machine, a casing, a plurality of coin-holders for coins of different denominations, a plurality of troughs on said casing, means for discharging coins from said holders, and adjustable means for guiding said coins into any of said troughs.

10. In a change-making machine, a casing, 115 a plurality of coin-holders for coins of different denominations, a plurality of troughs on said casing, a knob or handle exterior of said

casing, and means actuatable through said knob for guiding said coins into any of said troughs.

11. In a change-making machine, the combination of a longitudinally movable and rotatable disk having projections on its back, coin-holders having movable bottoms and pushers connected to said bottoms and adapted to be operated by the longitudinal movement of the disk, said disk being provided with a series of numbers around its periphery, adapted to coöperate with a corre-

sponding series of numbers on the casing, whereby the amount of change to be made is indicated by the difference between any two numbers brought opposite each other. 15

In testimony whereof I have signed this specification in the presence of two subscribing witnesses.

HAROLD BINNEY.
